UNITED STATES PATENT OFFICE.

OWEN A. GILL, OF BALTIMORE, MARYLAND, ASSIGNOR TO E. LEVERING & CO., OF SAME PLACE.

DESIGN FOR ORNAMENTING PAPER FOR COFFEE-PACKAGES.

SPECIFICATION forming part of Design No. 13,007, dated June 27, 1882.

Application filed February 12, 1881. Term of patent 14 years.

To all whom it may concern:

Be it known that I, OWEN A. GILL, a citizen of the United States, residing at Baltimore city, State of Maryland, have invented and produced a new and original Design for Ornamenting Paper and other Material, of which the following is a specification, reference being had to the accompanying engraving, forming a part thereof.

My design is intended for the ornamentation of paper or other material suitable for use as a package for coffee; and its leading feature consists in the representation of coffee-beans, substantially as they appear in the annexed engraving, or as they would appear when irregularly strewed over a surface. By

preference the figures of the beans are in substantial contiguity, some showing the convex and some the flat side of the bean; but they may be shown as more or less regularly distributed or arranged without departing from the general effect.

What I claim is—

The design for the ornamentation of paper or other material, consisting in the representation of coffee-beans distributed over a surface, substantially as set forth.

OWEN A. GILL.
